UNITED STATES PATENT OFFICE.

LE ROY W. FAIRCHILD, OF NEW YORK, N. Y.

DESIGN FOR A CHARM AND PENCIL-CASE.

SPECIFICATION forming part of Design No. 12,856, dated April 11, 1882.

Application filed April 5, 1881. Renewed March 18, 1882. Term of patent 7 years.

To all whom it may concern:

Be it known that I, LE ROY W. FAIRCHILD, a citizen of the United States, residing at the city of New York, in the county and State of New York, have invented a new and original Design for a Charm or Amulet, and which may, if desired, be used as a case for pencils or similar articles, of which the following is a specification.

10 The accompanying print from a wood-cut is a side elevation of my design and will serve to illustrate the same, and the following is a specification of the same, reference being had to the illustration forming part thereof.

15 The design consists of a chicken emerging from an egg-shell, as represented in the accompanying illustration, in which A represents the shell, and B the head and neck, of the chicken, which is represented as having its foot D and

its wing I exposed, as shown. To the back of 20 the neck is secured a ring, C, by which the article is to be suspended.

The several parts may be made of different metals or of different shades of the same metal, and thus be made to present a very ornamental 25 appearance.

The article is designed to be worn as a charm or amulet, and may be used as a case for a pencil or any similar small implement.

Having thus described my invention, what 30 I claim is—

The herein-described design, consisting of the shell A, with the chicken B and ring C, substantially as shown.

LE ROY W. FAIRCHILD.
